IRA LEON SLAWTER, OF GRAND PRAIRIE, ALBERTA, CANADA.

AUTOMATIC TIMER.

1,337,282.

Specification of Letters Patent. Patented Apr. 20, 1920.

Application filed March 5, 1919. Serial No. 280,775.

To all whom it may concern:

Be it known that I, IRA LEON SLAWTER, a subject of the King of Great Britain, and resident of the town of Grand Prairie, in the Province of Alberta, Dominion of Canada, have invented certain new and useful Improvements in Automatic Timers, of which the following is a specification.

This invention relates to improvements in automatic timers, which are also capable of being utilized as spark plugs, and the objects of the invention are to facilitate timing the spark of an internal combustion engine, so that ignition of the explosive mixture will take place at the proper moment, and thus a maximum power will be generated in the engine, to render the device capable of automatically adjusting itself to suit the conditions or load under which the engine is running, so that the spark will be sufficiently advanced under all circumstances to ignite the explosive mixture at that point at which the working stroke is about to commence, and to render the timer and spark plug self contained.

Further objects are to eliminate many of the parts which are at present utilized in the timing and ignition mechanism of internal combustion engines, to simplify the present device as far as possible, so that the upkeep of the engine will be cheapened and the liability of the several parts going out of repair will be greatly reduced.

Further objects are to eliminate leakage, and obviate the necessity of frequent repacking, and generally to render the several parts accessible for inspection.

Heretofore it has been found necessary when timing an engine to experiment with the engine under varying loads, and by adjusting the timing mechanism discover wherein the best results are obtained. This adjusting of the timing mechanism is manually performed and every load under which the engine is working calls for a manual adjustment of the timer to suit these conditions. Under the present invention the timer is initially set and automatically adjusts itself to the varying conditions under which the engine operates, and in this way insures the best results possible being obtained without any inconveniences which result with the timers at present in use.

With the above and other objects in view the invention consists essentially of the improved construction hereinafter described

and set forth in the following specification and accompanying drawings forming part of the same.

In the drawings:

Figure 1 is a fragmentary vertical section of the cylinder of an internal combustion engine with the improved timer and combined spark plug mounted thereon.

Fig. 2 is a vertical section of the improved timer and combined spark plug, the stem and sleeve being in elevation.

Fig. 3 is a plan view of the improved timer and combined spark plug.

Fig. 4 is a fragmentary vertical section of an internal combustion engine cylinder, showing the improved timer co-operating with an ordinary spark plug.

Like characters of reference refer to like parts in the several figures.

Referring to the drawings, A represents a cylinder of any usual construction and B the improved timer operatively mounted thereon. This timer comprises a casing of conducting material formed of two portions 80 10 and 11 threaded together, the portion 11 being internally threaded to engage with an adjusting nut 12, which is secured in the desired adjusted position by a set screw 13 threaded through the wall of the portion 85 11 of the casing.

Slidably operating in this casing is a stem 14 incased in insulating material 15, on which an outer sleeve 16 of conducting material is mounted, the sleeve 16 being provided intermediate of its length with a valve 17 faced on both sides and adapted to coact with the shoulder 18 formed in the interior of the lower portion 10 of the casing, or with the bottom of the threaded end of the portion 11, so that all leakage of combustible fuel is eliminated during the movement of the insulated stem 14 and sleeve 16.

This stem is designed to be held in its normal position by a spring 19 coiled there-around and located between the lower end of the nut 12 and the upper face of the valve 17.

The lower end of the casing 10 is provided with a tapered threaded portion 20 105 which engages with an orifice in the head of the cylinder A, and a contact 21 is secured to the threaded portion 20 and extends downwardly and below the stem 14 for an object which will be made clear hereafter.

On the upper end of the portion 11 of the casing an insulating washer of mica or

other suitable material 22 is secured, and on this washer a second washer of insulating material 23 is positioned and above this last said washer a third washer 24 of insulating material is positioned. It will be understood that the washers 22, 23 and 24 may be made in a single portion if such is found advisable or necessary.

Superimposed on the washer 24 is a conducting plate 25 having an arm 26 which is connected through the wire 27 with one portion of the wiring of an electric circuit, and the conducting plate 25 embraces the upper end of the insulated stem 14, the edge of the orifice in the plate being such that, on the longitudinal movement of the insulated stem and sleeve 16, contact will be made between the sleeve and the plate 25.

When the stem 14 and sleeve 16 have been moved in a longitudinal direction an electric circuit is closed, and the current flows through the wire 27, arm 26, contact plate 25, sleeve 16, the casing, the contact 21, the stem 14, and the wire 28 which is connected to the other portion of the wiring of the electric circuit, thereby closing the circuit which includes a suitable supply of electrical energy, and a spark is formed between the lower end of the stem 14 and contact member 21, such spark igniting the combustible mixture in the cylinder A bringing about the requisite explosion to drive the piston.

It should be particularly noticed that the circuit is completed on the longitudinal outward movement of the insulated stem 14 and sleeve 16, so that this movement should be controlled by the operation of the engine itself, and so permit of the timer being automatic in its action. To obtain this result I utilize the compression of the engine to move the insulated stem 14 and sleeve 16 outwardly, so that the closing of the circuit will at all times take place when a predetermined pressure limit has been exceeded within the cylinder A.

It will be clear that the spring 19 will require to be adjusted to the necessary tension, so that the insulated stem 14 and sleeve 16 will be returned to its normal position and break the circuit as soon as the compression in the cylinder falls below the predetermined limit, for which the spring is initially set.

When the insulated stem 14 and sleeve 16 are in normal position the valve 17 coacts with the shoulder 18 and prevents leakage of combustible fluid from the cylinder, and on longitudinal movement of the said stem 14 and sleeve, the valve 17 coacts with the lower threaded end of the portion 11 of the casing and prevents leakage of the combustible mixture.

To give an example of how this timing device is set, it may be preferable to consider

for one moment an automobile which is manually cranked during the starting operation, and in this case the spring 19 is tensioned, so that the insulated stem 14 and sleeve 16 will move longitudinally only when a maximum of energy has been applied by the operator to the hand crank lever, and in this way an explosion is obtained only when the compression of the engine exceeds that which could be overcome by hand cranking.

It will now be evident that should the compression in the cylinder not rise above that which is attained by hand cranking then no spark is obtained.

When the compression in the engine rises as the engine assumes normal working conditions and speed the compression increases and the spark will be automatically advanced to suit the compression obtained in the cylinder above that for which the spring 19 has been initially set.

It will be clear under those circumstances that the timer will automatically adjust itself to the load, so that ignition of the explosive mixture will take place at the proper point of the piston stroke of the engine to give the best possible results.

When the device is used exclusively as a timer, it acts in conjunction with an ordinary spark plug such as is illustrated at C in Fig. 4. In this case it will be understood that the wire 28 is dispensed with, and the plug C is connected to a wire 29 forming part of an electric circuit.

The contacting plate 25 is in this case provided with a wire 27 also connected to the electric circuit, and, when the insulated plunger 14 and sleeve 16 is moved longitudinally by the compression in the cylinder, the sleeve will contact with the contacting plate 25 closing a circuit including the contact 25, sleeve 16, the casing, earth through the cylinder, thence through the plug C which is also earthed, and through the wire 29, thereby creating a jump spark which will ignite the combustible fluid in the cylinder.

The operation of the timer in this case is the same as that already described, so that it is thought unnecessary to further enlarge upon the same.

The ignition will take place always as a predetermined compression is obtained for which the spring 19 is set and as the compression increases the spark is consequently advanced.

From this description it may be clear that I have invented a timer which is automatic in its action, and whereby the spark of an internal combustion engine will be automatically controlled, so that it is advanced as the compression exceeds a predetermined limit so that the engine itself controls the action of the device which is thus automatic.

and not liable to go out of order from any external cause.

As many changes could be made in the above construction, and many apparently 5 widely different embodiments of my invention, within the scope of the claims, constructed without departing from the spirit or scope thereof, it is intended that all matter contained in the accompanying specification and drawings, shall be interpreted 10 as illustrative and not in a limiting sense.

What I claim as my invention is:

1. A timer of the class described comprising a casing, a contacting member, a stem of 15 conducting material, an insulating member surrounding the stem, a conducting sleeve surrounding the insulating material, the said stem and sleeve being designed to be

moved outwardly when the pressure in the cylinder exceeds a predetermined limit, resilient means for returning the member to its normal position, and means for adjusting the said resilient means. 20

2. A device of the class described comprising a casing having spaced valve faces 25 therein, a member movable in the casing designed to make and break an electric circuit as the pressure in a cylinder exceeds and falls below a predetermined limit, and valve means located between said spaced valve 30 faces and designed to coact with either for preventing leakage about the stem and sleeve during the movement of the same.

In witness whereof I have hereunto set my hand.

IRA LEON SLAWTER.
